UNITED STATES PATENT OFFICE.

ISABELLE HENNE, OF BROOKLYN, NEW YORK.

DESIGN FOR A TREAD-PLATE FOR SHOE-HEELS.

53,502.

Specification for Design.

Patented July 8, 1919.

Application filed November 30, 1917. Serial No. 204,775. Term of patent 3½ years.

To all whom it may concern:

Be it known that I, ISABELLE HENNE, a citizen of the United States, and a resident of New York, borough of Brooklyn, in the county of Kings and State of New York, have invented a new, original, and ornamental Design for a Tread-Plate for Shoe-Heels, of which the following is a specification, reference being had to the accompanying drawing, forming a part thereof.

In the drawing, the figure is a perspective

view of a tread plate for shoe heels embodying my ornamental design.

I claim:—

The ornamental design for a tread plate for shoe heels as shown.

This specification signed and witnessed this 28th day of November, A. D. 1917.

ISABELLE HENNE.

Witnesses:

E. W. JONES,

C. M. SCHOBER.
